[57] CLAIM

The ornamental design for a combined ceiling fan and light fixture, as shown and described.

DESCRIPTION

FIG. 1 is a perspective view of the combination of the present invention, showing a first embodiment of the new design;

FIG. 2 is a side elevation view of the embodiment shown in FIG. 1, on a reduced scale;

FIG. 3 is a top plan view of the embodiment shown in FIG. 1, on a reduced scale;

FIG. 4 is a bottom plan view of the embodiment shown in FIG. 1, on a reduced scale;

FIG. 5 is a perspective view of the embodiment shown in FIG. 1 with the light fixture portion of the design moved to a different location;

FIG. 6 is a perspective view of a second embodiment of the new design; and,

FIG. 7 is a perspective view of a third embodiment of the new design.

The sole difference between the first and third embodiments is the number of lights. The sole difference between the first and second embodiments is that the light fixtures are composed of transparent or semi-transparent (e.g., frosted) glass material in a petal-type design (FIG. 6), as opposed to solid-metal canister-type lights. FIG. 5 indicates that the lighting assembly may be moved along the down-rod a distance from the fan assembly.

FIG. 1

FIG. 2

FIG. 3

FIG. 4

FIG. 5

FIG. 6

FIG. 7
